UNITED STATES PATENT OFFICE.

EDWARD D. PUTT, OF AKRON, OHIO, ASSIGNOR TO THE FIRESTONE TIRE AND RUBBER COMPANY, OF AKRON, OHIO, A CORPORATION OF OHIO.

BEAD-COVERING MACHINE.

Application filed February 23, 1925. Serial No. 12,243.

This invention relates to machines for covering bead material such as is used in the construction of pneumatic tires and particularly tires of the clincher type.

5 The purpose of the invention is to provide an improved machine for progressively applying a strip of rubberized fabric about a strip of bead material, usually of rubber composition, in preparation for use in the 10 building of tires.

One object of the invention is to provide a 15 table onto which the bead strip and the cover strip are guided, instrumentalities for guiding the strips in proper relation onto the table and instrumentalities for progressively folding 20 the fabric strip about the bead strip.

The foregoing and other objects are obtained by the construction shown in the accompanying drawings and described in detail 25 below. It is to be understood that the invention is not limited to the specific construction shown and described.

Of the accompanying drawings:

Figure 1 is a plan of a machine constructed 30 in accordance with the invention and illustrated as in operation;

Figure 2 is a side elevation thereof;

Figure 3 is a section on line 3—3 of Figure 1;

35 Figure 4 is a section on line 4—4 of Figure 1;

Figure 5 is a section on line 5—5 of Figure 1;

Figure 6 is a section on line 6—6 of Figure 1;

40 Figure 7 is a section on line 7—7 of Figure 1;

Figure 8 is a section on line 8—8 of Figure 1;

45 Figure 9 is a section on line 9—9 of Figure 1;

Figure 10 is a section on line 10—10 of Figure 1; and

Figure 11 is a section on line 11—11 of Figure 1.

Referring to the accompanying drawings 50 represents a table forming a part of the machine and mounted on a suitable standard 11. For guiding the covering strip 12 onto table 10 from any suitable source a downwardly curved guide member 13 is secured onto one end of table 10, the member 13 having upstanding guiding flanges as indicated at 14 thereon. For accurately positioning the fabric strip 12 on the table 10, guide bars 15,

15 are provided between which the strip passes from guide 13. The bars 15 are arranged to be secured in various adjusted positions from or toward each other with respect to table 10 being secured on table 10 60 by thumb screws 16, 16 operable in slots 17, 17 in an extension plate 18 secured on the leading end of table 10. After passing from between the bars 15 the strip 12 is folded over the bead strip away from the near side of the 65 machine, as shown in Figure 1, and to prevent the strip 12 from being drawn out of place between the guides 15 by this action a roller 19 is journaled over the near bar 15 so as to overlie the strip. 70

Arranged for guiding the bead strip indicated at 20 into proper relationship onto the strip 12 on table 10, a roller 21 formed with a transversely grooved face is journaled on a bracket arm 22 so as to overlie guide 13 and 75 adapted to have the bead strip 20 pass thereover. A pair of guide brackets 23 and 24 are also employed to accurately position the bead strip 20 on the fabric strip 12. One of these brackets 23 is secured on plate 18 and 80 the other 24 is sliding thereon being normally urged toward bracket 23 by a compression spring 25. A spindle 26 is secured in bracket 23 by a compression spring 25. A spindle 26 is secured in bracket 23 and a third bracket 27 on plate 18 and extends through bracket 24 and spring 25. A roller 28 is journaled on spindle 26 between brackets 23 and 24 and adapted to retain the strip 20 85 thereunder and between the brackets. 90

It is necessary to press the strip 20 into intimate contact with the strip 12 when properly positioned thereover and to this end a presser roller 29 is provided, the roller 29 being adapted to engage strip 20 as shown in 95 Figure 3. The roller 29 preferably is journaled on an extension 30 on bracket 23. A positioning roller 31 is arranged to engage under the "heel" of the bead strip 20 to prevent lateral displacement of the bead strip on strip 12 by roller 29. The roller 31 is journaled on a bracket 32 secured onto bracket 24 and is accordingly yieldingly urged against strip 20 by spring 25. 100

In order to prevent adhesion of the strip 12 to the table 10, the strip 12 is supported under roller 29 by a knurled roller 33 operating through a slot 34 in the table 10 and which may be and preferably is driven to feed the strips 12 and 20 over table 10 as by being 110

secured on a shaft 35 journaled in brackets indicated at 36 on the under side of table 10. Shaft 35 has a drive sprocket 37 thereon over which is trained a chain 38 driven by a sprocket 39 on a shaft 40 which is journaled on standard 11 and may be driven by a gear 41 adapted to be driven by suitable power means (not shown).

Extending longitudinally of table 10 is a plate 42 on which the various folding instrumentalities are mounted and over which the strips 12 and 20 are accordingly conducted. For first folding one side of strip 12 over bead 20 a folding shoe 43 is mounted on plate 42 in the path of strip 12 (see Figure 4). For holding strip 20 against the folding action of shoe 43 a roller 44 is provided for engaging under the "heel" of the bead strip and is held thereagainst by being journaled on an arm 45, pivoted at 46 on table 10 and secured in place by a screw 45^a.

To continue the folding action of shoe 43 a series of folding rollers 49, 50, and 51 are provided, each roller being journaled on a vertical stud respectively indicated at 49^a, 50^a, and 51^a (Figures 5, 6, and 7). Each roller 49, 50, and 51 is formed with a peripheral groove of the profile of the "toe" of bead strip 20 so as to press strip 12 thereagainst and each is formed with an upper flange 49^b, 50^b, and 51^b progressively increasing in diameter in the order named to progressively fold and press the strip 20 onto the upper surface of the bead. In order to hold the strip 20 against the rollers 49, 50, and 51 with the "toe" thereof snugly fitting into the grooves in said rollers, a series of rollers 52, 52 similar to rollers 44 are provided for engagement under the "heel" of the bead strip. The rollers 52 are also similarly mounted on arms 53, 53 pivoted at 54, 54 on table 10 and yieldingly urged against the bead strip 20 by springs 55, 55 connected between the various arms 53 and a stud 48. For completing the folding of strip 12 onto the upper surface of strip 20 a final pressure roller 56 is employed (Figure 8). This roller is cylindrical and is journaled on a bracket 57 secured on plate 42. Since pressure of the various rollers 49, 50, 51 and 56 on the strip 20 would tend to cause great friction of the tacky stock 12 on plate 42, a series of bearing rollers 58, 58 are journaled under said pressure rollers in a slot 59 in plate 42 to prevent binding of the stock in the machine.

Arranged for the next operation on strips 12 and 20, namely folding the former about the "heel" of the latter, a roller 60 is provided. The roller 60 is in the form of a disk rotatable in a vertical plane on a spindle 61 secured in a bracket 62 on table 10, and is adapted to fold strip 12 about the "heel" of strip 20 in the manner shown in Figure 9.

The side of the bead 20 under the "heel" is concave in section and accordingly for forming the strip 12 about this portion, there is

next provided a roller 63 formed with a peripheral profile adapting it to fit said side of bead 20 (Figure 10). The roller 63 is journaled on an inclined spindle 64 mounted in a bracket 65 adjustable on a second bracket 65^a 70 which latter is mounted on frame 10. The upper portion of roller 63 is roughened or knurled as at 63^a for engagement with the strip 12 over the "heel" of the bead to insure driving of roller 63 and proper pressing of the strip 12 into place. A presser roller 66 is arranged to cooperate at the same time with the "toe" and upper surface of strip 20 to more thoroughly press strip 12 thereon and to prevent displacement thereof by action of roller 63. Roller 66 is accordingly of the profile shown in Figure 10 and is also journaled onto an inclined spindle 67 secured in a bracket 68 adjustable on a second bracket 69 which latter is mounted on table 10.

To provide a bearing for strip 20 under rollers 63 and 66 and also to drive the strip, a roughened roller 70 operating through a slot 71 in table 10 is arranged to engage the under side of the strip. The roller 70 is secured on a shaft 72 journaled under table 10 and driven by a sprocket 73 over which passes a chain 74 driven by a sprocket 75 on shaft 35 so that rollers 33 and 70 are driven in unison and at the same speed.

A set of rollers 76 and 83 are arranged for a final bead pressing and driving action. The roller 76 is formed with a peripheral groove of the profile of the top of the bead strip (Figure 11) and is journaled on an arm 77 pivoted at 78 on table 10 and urged by a spring 79 downwardly against the strip 20, the pressure of spring 79 being adjustable by operation of a thumb-screw 80 on a threaded rod 81, encircled by the spring and extending through an apertured lug 82 on arm 77, the rod 81 being secured on table 10.

The roughened roller 83 rotates through a slot 84 in table 10 and engages the under surface of strip 20 (Figure 11). It is driven by a shaft 85 journaled on the under side of table 10 and driven by a sprocket 86 over which is trained a chain 87 which is driven by a sprocket 88 on shaft 72. Accordingly roller 83 is driven in unison and at the same speed 105 with rollers 33 and 70.

The operation of the device which will be understood from the foregoing may be briefly summarized as follows:

A strip 12 from a suitable source (not shown) is guided onto table 10 between bars 15 and over roller 33. A strip 20 from a source of supply (not shown) is guided onto strip 12 on table 10 by being passed over roller 21 under roller 28 between guides 23 and 24 and under roller 29 onto strip 12. The rollers 33, 70, and 83 are then continuously driven and strips 12 and 20 are thus drawn through the machine, the strip 12 being progressively formed about the bead strip 20 in the manner 136

shown in Figures 3 to 11 which illustrate the operations of the machine in the sequence in which they are performed. The portion 12^a of strip 12 is left unfolded as shown in Figure

5 11 to provide means for anchoring the bead in a tire carcass.

It will be apparent from the foregoing that the machine of the invention is adapted rapidly and effectively to cover continuous bead 10 strips in preparation for use in tire building. Modifications of the invention may be resorted to without departing from the spirit thereof or the scope of the appended claims.

What is claimed is:

15 1. Apparatus for continuously folding a strip of fabric about and pressing it onto a strip of bead material comprising a support including a series of rollers on which said strips are carried, means for guiding the 20 strips into contact with each other on said support, means for driving the composite strip thus formed over said support, means for progressively folding and pressing said fabric strip onto said bead strip said means 25 including a series of rollers whose axes are perpendicular to said support, whose peripheries are positioned to be tangential to the bead material and formed with flanges for overlying said composite strip, said flanges 30 being of progressively increasing diameters, and means for pressing the bead strip against said rollers.

2. Apparatus of the class described comprising a support, means for guiding a fabric 35 strip thereon, means for guiding a bead strip thereon, means for pressing said strips together, means for progressively folding said fabric strip about said bead strip, said means including a series of rollers journaled on said 40 support so that their axes are substantially perpendicular to said support with their peripheral portions positioned to be tangential to the bead strip and formed with flanges for overlying said bead strip, said flanges being 45 of progressively increasing diameters, and means for holding the bead strip against the rollers.

3. Apparatus of the class described comprising a support, means for feeding a strip 50 of fabric having a strip of bead material thereon over said support means for folding and shaping said fabric about said bead material including a series of rollers journaled on said support, the axes of said rollers being 55 substantially perpendicular to said support with the peripheries thereof positioned to be tangential to the bead material and said roll-

ers being formed with progressively larger folding flanges for overlying said bead strip, and means for guiding the core strip into contact with the peripheries of the rollers.

4. Apparatus of the class described comprising a support, including a series of bearing rollers, means for feeding a strip of fabric having a strip of bead material thereon over 60 said support means for folding and shaping said fabric about said bead material including a series of rollers journaled on said support, the axes of said rollers being substantially perpendicular to said support and the peripheries thereof being so positioned as to be tangential to the bead material and said rollers being formed with progressively larger folding flanges overlying said bead strip, and means for guiding said bead material in contact with the peripheries of said rollers.

5. Apparatus of the class described, comprising means for continuously feeding a core strip and a covering strip into juxtaposition, means for folding the covering strip about the core strip comprising a series of rollers, the peripheries of which are adapted to be tangentially engaged by one edge of the core strip, said rollers having flanges for extending over the core strip, said flanges being of 80 progressively increasing diameter, and means for urging the core strip against the peripheries of said rollers including a series of rollers yieldingly urged against the other edge of 85 the core strip.

6. Apparatus of the class described, comprising means for continuously feeding a core strip and a covering strip into juxtaposition, means for folding the covering strip about the core strip comprising a series of rollers, the peripheries of which are adapted to be tangentially engaged by one edge of the core strip, said rollers having flanges for extending over the core strip, said flanges being of 90 progressively increasing diameter, and means for urging the core strip against the peripheries of said rollers including a series of rollers yieldingly urged against the other edge of 95 the core strip.

7. Apparatus of the class described, comprising means for continuously feeding a core strip and a covering strip into juxtaposition, and means for folding the covering strip about the core strip comprising a series of rollers, the peripheries of which are adapted to be tangentially engaged by one edge of the core strip, said rollers having flanges for extending over the core strip, said flanges being of 100 progressively increasing diameter, and means for urging the core strip against the peripheries of said rollers.
